(57) **CLAIM**

We claim the ornamental design for a box for packaging, as shown and described.

DESCRIPTION

FIG. 1 is a perspective view of a box for packaging, showing our new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof;

FIG. 8 is a perspective view showing a configuration of use wherein a top cover of an outer box is open;

FIG. 9 is a front elevational view thereof;

FIG. 10 is a rear elevational view;

FIG. 11 is a left side elevational view thereof;

FIG. 12 is a right side elevational view thereof;

FIG. 13 is a top plan elevational view thereof;

FIG. 14 is a bottom plan elevational view thereof;

FIG. 15 is a perspective view showing another configuration of use wherein an inner tray is pulled out from the outer box;

FIG. 16 is a front elevational view thereof;

FIG. 17 is a rear elevational view thereof;

FIG. 18 is a left side elevational view thereof;

FIG. 19 is a right side elevational view thereof;

FIG. 20 is a top plan view thereof; and,

FIG. 21 is a bottom plan view thereof.

The dash-dash broken lines in the drawings show portions of the box for packaging which form no part of the claimed design. The dot-dash broken lines shown in FIGS. 1, 2, and 6 depict lines along which a portion of the box for packaging may be torn.

1 Claim, 16 Drawing Sheets
